STENCIL PRINTING APPARATUS

Harmon P. Elliott, Watertown, Mass., assignor to
 Elliott Addressing Machine Company, Cambridge, Mass., a corporation of Massachusetts

Application July 28, 1934, Serial No. 737,336

3 Claims. (Cl. 101—50)

It has been the special object of my invention to create an apparatus which shall permit the automatic, unlimited repetition of a cycle of operation upon a group of stencils, so that a series 5 of printed elements, such as cards or paper sheets, may be repeatedly reproduced, by stencil printing, in the same order of reproduction and without the necessity of manually reassembling and restacking the separate stencils and placing them 10 again and again in feeding position in the machine according to the long established practice.

This I have accomplished by organizing a group of stencils into a flexible, endless strip and providing means to bring each of the individual 15 stencil elements forming the strip into repeated engagement with a card, sheet or other element to be printed upon, and to bring the stencil element and card into joint cooperative relationship with the printing means. The result is to afford 20 to the stencil printing art, which is so capable of practice by unskilled operators, a device which shall perform the automatic continuous reproduction of a series of printed cards or sheets in a rapid and convenient manner.

25 In the following described machine in which I have incorporated the above mentioned endless flexible strip composed of individual stencil elements, I have embodied several features already old and well known in the stencil printing art and 30 in some instances described and shown in patents which I shall hereinafter mention.

My device may be best understood by reference to the accompanying drawings in which—

35 Fig. 1 is a front elevation of a preferred type of stencil printing machine having my improvements embodied therein.

Fig. 2 is a medial longitudinal sectional view of the entire machine.

40 Fig. 3 is an enlarged top view of the clutch by means of which the motor driving power is transferred to the printing mechanism and other moving parts of the machine.

45 Fig. 4 is an enlarged front view of the driving gear and accompanying clutch engagement elements mounted in the hub thereof.

Fig. 4a is a sectional view on line 3—3 of Fig. 3 showing the face of the hub of the fixed element of the clutch mechanism with its inset dogs for clutch engagement.

50 Fig. 5 is a sectional view on line 5—5 of Fig. 3 showing the clutch release bar in the operative position.

Fig. 6 is a cross section on line 6—6 of Fig. 5 showing the conformation of the operative end of 55 the clutch release bar.

Fig. 7 is an enlarged transverse view showing the arrangement of the stencil strip actuating sprocket roller and associated upper and lower rollers for holding the strip in engagement with the sprocket roller, and also the conveyer for spreading out and removing from the machine printed cards or sheets, together with the mechanism for actuating the said conveyer.

Fig. 8 is an enlarged top view of the stencil strip and actuating parts shown in Fig. 7 with a 10 stencil strip in operative engagement therewith.

Fig. 9 shows an individual stencil element.

Fig. 10 is an enlarged rear view of the ink distributing and printing rollers, showing, in medial longitudinal section, the front end and outlet control means of the card or sheet feed hopper and adjacent card or sheet forwarding and guiding means.

Fig. 11 is a view on line 11—11 of Fig. 10 showing the assemblage of inking and printing rollers 20 and their actuating and control parts.

Referring now more specifically to the drawings, in which like reference numbers indicate like parts, 1 is a platform or table supported by legs 2. Mounted on the top of the table by means of legs 25 3 is the main machine frame 4 which is provided with opposite upward extensions 5 and 6 (see Fig. 11). Mounted beneath the platform 1 is an electric motor 7, the driving shaft 8 of which is attached by the coupling 9 to the shaft 10 of a suitable reduction gear mechanism 11 which is bolted to the under side of the platform 1. The reduction gear mechanism 11 has a transverse shaft 12 which has fixed thereon a pulley 13 having an enlarged hub 14 carrying dogs 15 arranged normally to contact with a cylindrical pin 16 pocketed in hole 17 in the hub 18 on a sprocket gear 19 which is loose on the shaft 12. The cylindrical pin 16 is normally thrust outwardly against the end of the hub 14, so that it may engage a dog 15, 40 by the coil spring 20 pocketed in the base of the cylindrical hole 17. The hub 18 has a deep annular channel 21 and the pin 16 has a reduced portion 22 into which may enter the wedge shaped end 23 of the clutch operating arm 24 which, when in the position shown in Fig. 5, will, upon the rotation of the sprocket gear 19, engage the rearward shoulder of the larger part of the pin 16 and, upon the continued rotation of the gear 19, force the retirement of the pin 16 so as to 45 prevent the driving engagement of a dog 15 therewith.

The clutch operating control arm 24 is normally supported in an elevated position so as to cause clutch release by a cam roller 25 operated 55

by the control lever 26, which will, when moved forward, permit the arm 24 to drop, swinging on its pivot 30, thereby causing clutch engagement. A coil spring 27 attached at its top to the clutch 5 operating control arm 24 and at its lower end to a bracket 28 depends from the platform 1 and keeps the clutch control arm 24 in firm engagement with the cam roller 25.

The pulley 13 carries a flexible endless belt 10 31 the upper end of which passes about a driving pulley 32 fixed on the end of a shaft 33 transversely and rotatably mounted in the frame extension sides 5 and 6 (see Figs. 1 and 11). The shaft 33 has fixed thereto a rubber faced ink 15 distributing roller 34, which is rotating at all times when the driving motor 7 is in operation.

The sprocket gear 19 on the shaft 12 carries a sprocket chain 35 which passes about a sprocket gear 36 attached to a rotatable shaft 37 mounted 20 transversely in the frame 4 (see Fig. 11). The rotatable shaft 37 has also fixed thereon a segmental inking roller 38 and a gear 37a which meshes with a gear 37b fixed on the rotatable shaft 37c on which is fixed a segmental platen 25 roller 42 which underlies and cooperates with the segmental inking roller 38.

As means for supplying ink to the segmental inking roller 38 I have provided the roller shaped ink reservoir 39 with small holes 40 on a limited portion of its periphery. This ink reservoir 39 is rotatably mounted on trunnion pins 41 which are eccentrically disposed in hubs 41a which are connected by the yoke 43, and which are loosely and rotatably supported in the forked extremities 44 and 45 of the frame extensions 5 and 6 respectively. The thumb piece 46 is attached to one of the hubs 41a so that the operator may conveniently give a partial rotation to the hubs 41a thereby causing the ink reservoir roller 39, because of its eccentric mounting, to be pressed into engagement with the rubber faced roller 34 on the shaft 33. When the operator releases the thumb piece 46 the weight of the yoke 43 will cause the ink reservoir roller 39, upon the partial rotation of the hubs 41a, to be raised out of contact with the roller 34. The ink reservoir roller 39 is weighted internally on its inner periphery so as to cause it to rotate automatically sufficiently to bring the ink dispersing holes therein above the liquid level of the ink when it is lifted out of contact with the roller 34. Such an inking device is generally described and claimed in my Letters Patent of the United States, No. 1,614,547, dated January 18, 1927.

Beneath the intermediate inking roller 34 is mounted a pair of felt faced ink absorbent rollers 48 (see Figs. 10 and 11). These rollers 48 are mounted upon a frame 49 by means of shafts 50 which extend between opposite ends of the frame 49 which is centrally mounted on a cross shaft 51 which is rotatably supported between the sides 5 and 6 of the frame extension. The frame 49 carries an upwardly extending arm 52 upon which is loosely pivoted at one end the connecting rod 53, the other end of which is eccentrically pivoted on a gear 54 rotatably mounted on a bracket 55 fixed to the side of the frame 5. The gear 54 meshes with a worm gear 56 fixed on the shaft 33 so that upon rotation of shaft 33 the gears 56 and 54 will rotate thereby causing the connecting rod 53 to reciprocate the frame 49 and the rollers 48 thereon mounted, so as to cause a wiping contact between the rollers 48 and rollers with which they engage, so as better to spread the ink. The shaft 51 is

provided with a slot or groove on its end surface which is entered loosely by a pin 57 extending through the central portion of the frame 49 so that the angular position of the shaft 51, upon being set by the crank 58, which is under the eccentric tension of spring 59, will cause one or the other of the felt faced rollers 48 to contact with the intermediate inking roller 34 while its opposite roller 48 bears upon the lower rubber faced intermediate inking roller 60 which is freely rotatable upon a cross shaft 61 mounted between the sides of the frame extensions 5 and 6. The lower end of the spring 59 loosely embraces the end of the shaft 61. The shaft 61 has a reduced and slightly eccentric portion 62 on which the roller 60 is mounted and the reduced end enters in an eccentric position an annular hub 63 which is fixed on the reduced end portion 62 of the shaft 61, the hub 63 being concentric with the shaft 61, so that a partial rotation of the hand wheel 64 will cause the roller 60 to be slightly elevated and removed from contact with the rubber faced segmental roller 38, an operation which is desirable if the machine is to be left idle for a substantial period of time since otherwise the contacting surfaces of rollers 60 and 38 might become flattened or distorted so as to impair the effectiveness thereof.

A sprocket gear 67 fixed on the shaft 37 is connected by the sprocket chain 68 with a sprocket gear 69 fixed on the shaft 70 which is rotatably mounted between brackets 4a mounted on the base of the frame 4 (see Figs. 1, 7, and 8). The shaft 70 has fixed thereon a sprocket roller 71 provided with parallel rows of sprocket teeth 72 spaced to engage the symmetrically spaced perforations 73 along the edges of a stencil strip 74, which stencil strip is arranged to form an endless belt supported by a curved elevated guideway 75 provided with flanges 76, the guideway 40 75 being supported by arms 77 and 78 extending upwardly from the frame extension 6. The end of the loop formed to the right of the stencil strip feed sprocket roller 71 after passing over the curved guideway 75 is positioned by a curved 45 guideway 79 so that it will pass between the segmental rollers 38 and 42 before passing again into engagement with the sprocket roller 71 and continue to the left to form a loop as shown in Figs. 1 and 2 which loop may bear against one 50 or both of the idler rollers 80 and 81 mounted between parallel spaced posts 82 mounted upon the platform 1.

The endless strip of stencil units, organized as above described, is formed of separate elements or units, as shown in Fig. 9, which are provided with a frame 83 made preferably of a strong but flexible paper and provided with a window or opening 84 which is covered by a thin strip of coated tissue paper, such as the well known "Yoshimo" paper commonly employed for making coated tissue paper stencils of the well known type provided with a coating which may be written or drawn upon by a stylus or written upon by a typewriter, so that the stencil becomes 65 impervious to ink where the ink impervious coating has been cut through by the stylus or by type of the typewriting machine. Of course, each stencil is prepared for use, by writing or drawing thereon, before the separate units are 70 assembled into the strip 74 which is preferably done by the use of thin, short wire clips or staples 85 which may be readily attached by any one of several well known machines or hand de- 75

vices now commonly in use for attaching together sheets of paper.

The upper and lower parts of the endless stencil strip 74 are maintained in firm driving engagement with the sprocket roller 71 by means of upper and lower pairs of yieldably mounted clamping rollers 86 which have annular reduced portions 87 to permit the passage of the sprocket teeth 72 upon the roller 71. The upper pair of clamping rollers 86 is mounted upon and between a pair of bracket plates 88 (see Figs. 7 and 8) each of which is slidably supported upon one of the outer faces of the opposite sides of brackets 4a and yieldably held downward by a coil spring 90 attached at its upper end to a pin 91 attached to a bracket plate 88 and at its lower end to a pin 92 attached to the adjacent side of a bracket 4a and passing through a slot 93 in the bracket plate 88. The lower pair of clamping rollers 86 is yieldably held upward against the sprocket roller 71 by the pull of spring 94 attached at its top to the frame 4 and at its lower end to a bar 95 (see Fig. 1) which is a part of a frame 96 having forked extensions 97 in which are journaled the lower pair of clamping rollers 86. The bar or member 95 of the frame 96 is pivoted by a pivot 98 upon a post 99 attached to the frame 4. It may be readily understood that this yieldable mounting of the clamping rollers 86 is for the purpose of permitting an end of the stencil strip 74 to be threaded into engagement with the roller 71 and led over the guideway 75 and around the guideway 79 and through the opening between the segmental rollers 38 and 42 and thence beneath the sprocket roller 71, before the ends of the strip 74 are joined together to form a continuous belt or strip which has a loop embracing the idler rollers 80 and 81. A feed roller or drum 101 for feeding the cards or sheets to be printed upon is fixed upon a shaft 102 rotatably mounted between the sides of the frame 4. The larger part of the periphery of the drum 101 is smooth but it bears upon a limited part of its periphery a corrugated rubber friction plate 103. The shaft 102 of the feed drum 101 has attached thereto a sprocket gear 104 about which passes a sprocket chain 105 which engages a similar sized sprocket gear 106 (see Fig. 11) which is fixedly mounted on the shaft 41 supporting the lower segmental roller 42 so that power taken from the shaft 41 may drive the feed drum 101. The shaft 102 also has fixed thereon a pulley 107 which carries a belt 108 which engages a pulley 109 (see Figs. 1 and 10) fixed to a shaft 110 rotatably mounted between the sides of the frame 4, which pulley 109 has attached thereto and rotatable therewith a feed roller 111. The upper part of the periphery of the feed roller 111 extends through a slot 112 to a height slightly above the top of a transverse feed bed 113 in the frame 4.

Mounted on the frame 4 above the feed drum 101 is a feed hopper 114 having side walls 115 and a front wall 116 (see Figs. 1 and 10) which feed hopper is of a general type now long in use, the base 117 of which supports only the rearward part of the stock of cards or sheets 118 placed therein, the lowermost card resting at its front part on the top of the drum 101 so that the lowermost cards may successively be fed forward one at a time, by engagement of the corrugated rubber strip 103 upon the periphery of the drum 101, through the opening beneath the stop blade 119 which is slidably held against the adjacent rear face of an inset portion 120 of

the front wall 116. The stop blade 119 is retained in position by screws 121 which pass through slots 122 in the inset portion 120 of the front wall 116 and through spring plates 123 and 124 and stiff plate 125 and the adjusting bar 126, 5 the position of which bar is controlled by a screw 127 having a knurled thumb-nut 128, which screw 127 passes through a threaded block 129 attached to the front face of the top part of the front wall 116. The lower end of the adjusting 10 screw 127 passes freely through a hole in the bent-over top 130 of the adjusting bar 126 and is engaged in fixed but rotatable relation with the adjusting bar 126 by means of collars 131 and 132 which are fixed on said adjusting screw 15 127.

Above the feed roller 111 is an idler roller 134 which is mounted between the sides of a bracket 135, the back of which is clamped between the lower extremities of the spring plates 123 and 124. A presser plate 136 has a forked rearward extremity which straddles the roller 134 and is pivotally mounted on a pin 137 which extends between the sides of the bracket 135. The forward ends of each side of the bracket 135 rest 25 upon the top of the presser plate 136 and thus the presser plate 136 and the idler roller 134 are normally forced downward under the tension of the spring plates 123 and 124 so as to hold an advancing card from the stack 118 firmly against 30 the feed roller 111 and the feed bed 113.

A belt conveyer 140 (see Figs. 1, 2, and 7) for spreading out and removing from the machine the printed cards or sheets, is mounted upon rollers 141 and 142 journaled at opposite ends of a frame 143, which frame is supported on legs 144 attached to the platform 1. The shaft 142a to which is fixed the roller 142 has attached thereto a ratchet-wheel 145 engaged by a pawl 146 pivoted in a link 147, which pawl 146 is held against 40 the ratchet-wheel 145 by the spring 148. The movable end of the link 147 is given reciprocating action by the loosely, pivotally connected rod 149, which is slidably mounted on a post 4b which is attached to the frame 4, by means of the large 45 heads of pins 150, which pass freely through slots in the rod 149. The rod 149 bears upon and is actuated by a cam 151 fixed upon the shaft 70, being held in yielding contact therewith by the coil spring 152, the upper end of which is attached 50 to a pin 153 attached to the frame 4, and the lower end of which is attached to a pin 154 which passes through a slot 155 in the post 4b and is fixed in the rod 149.

A sprocket chain supporting wheel 160 is mounted on a bracket 161 adjustably fixed on the frame 4 by means of screws 162 which pass through slots in the bracket 161. A stop plate 163 is mounted on a bracket 164 attached to the frame and serves to intercept the printed cards as they 60 are projected from between the segmental rollers 38 and 42 and cause them to fall upon the conveyer belt 140.

From the foregoing description the general operation of my device may be readily understood. 65 It is to be understood, however, that prior to operation the position of the stencil strip 74 is so adjusted, by engagement with the sprocket roller 71, that an individual stencil will be engaged by the advancing edge of the segmental 70 printing roller 38, as it rotates with clockwise motion, at a point closely adjacent to the advanced edge of the thin stencil sheet covering the window 84. Then as the rotation of the segmental roller 38 continues it will press down 75

upon the entire extent of the thin stencil paper covering the window 84 since the peripheral length of the segmental roller 38 coincides substantially with the length of the window opening 84, and, during the interval when the segmental printing roller 38 is not in engagement with the stencil strip, the stencil strip will advance sufficiently under the influence of the feed roller 71, to bring the next succeeding unit of the stencil strip into correct printing alignment with the segmental printing roller 38, the cut-away portions of the peripheries of the segmental rollers 38 and 42 being sufficient to permit this. It is to be noted that the roller 71 and the segmental rollers 38 and 42 have the same gearing and substantially identical peripheral speeds. The segmental platen roller 42, revolving in identically timed relation with the segmental printing roller 38, but in the opposite direction, will support each card to be printed, as the cards are successively advanced into printing position beneath the stencil strip 74. The position of the feed roller 111 with respect to the cooperating segmental rollers 38 and 42 is such that when a card or sheet from the feed hopper 114 advances beyond the influence of the feed roller 111 it is immediately brought to a stop, by the frictional drag of the presser plate 136, in correct position for proper registration with the overlying stencil unit 30 through which it receives an imprint. As the gearing is such that the feed drum 101 makes one revolution for each revolution of the segmental rollers 38 and 42 and the feed roller 71, which actuates the stencil strip, a card or sheet is advanced from the feed hopper 114, through the influence of the friction strip 103, to meet each individual stencil as it is advanced under the segmental printing roller 38.

As the cards or sheets which have been printed 40 upon pass from under the influence of the cooperating segmental rollers 38 and 42 they are projected against the stop member 163 and fall upon the top of the conveyer belt 140 which is given successive intermittent movements toward the 45 roller 141 through the action of the cam 151 upon the rod 149 and the pawl-bearing link 147, the pawl 146 of which engages the ratchet wheel 145. Hence the printed cards or sheets are fanned out upon the top of the belt conveyer 140 and, 50 by placing any convenient marking devices upon the belt conveyer 140 to indicate the beginning and end of a cycle of printing operations, the operator may remove from the belt, from time to time, complete sets of the printed cards and thus 55 keep the printing operations uninterrupted, as the operator may, in intervals between the removal of sets of printed cards, from time to time, replenish the stack of cards in the feed hopper 114.

60 It is obvious that many ways may be devised for supporting the endless strip of stencils but it is preferable to do so with as few abrupt changes of direction as possible in order that there may be a minimum frictional drag upon the rather frail 65 paper structure of the stencil frames 82, and consequently I find my particular means of mounting and supporting the endless stencil strip, whereby that part thereof which lies to one side of its feed sprocket roller 71 passes over the curving guideway 75, is very advantageous since the curved guideway 75 may be adjustably mounted in a considerably more elevated position if it is desired to deal with a larger endless stencil strip; and, moreover, that part of the stencil strip 74 which 75 lies in a loop to the other side of the feed sprocket

roller 71 may be considerably lengthened without any change in the structure of the machine so that my device may readily accommodate endless stencil strips of varying length.

It is, moreover, to be noted that since the stencil strip is in feeding engagement with opposite parts of the periphery of the sprocket roller 71 the loop thereof which passes over the curved guideway 75 and around the curved guide plate 79 is kept constant in extent and may be set in rather loose relationship with these elements so that there is no heavy frictional drag thereon, either because of the actuating force of the sprocket roller 71 or the influence of the cooperating printing and platen rollers since these rollers have substantially the same peripheral speed as that of the sprocket roller 71 which keeps the stencil strip in continuous movement. It will be observed, therefore, that the relatively free loops of the stencil strip lying to either side of the sprocket roller 71 are supported and moved with a minimum of stress upon the rather fragile structure of the stencil strip, which is, of course, very important.

The particular means which I have shown for stacking and forwarding the cards or sheets to be 25 printed upon is substantially that described and claimed in my Letters Patent No. 1,694,619, dated December 11, 1928, for addressing machines, and I have also employed in my machine herein described means for printing upon the cards or 30 sheets through a superimposed stencil passing, with the card or sheet, between segmental rollers embodying features described and claimed in my Patent No. 1,908,910 of May 16, 1933, which patented devices, however, deal with stencils fed forward intermittently from a stack into cooperative relationship with the card, sheet or envelope to 35 be printed upon.

It will be readily understood that there may be 40 many changes in the details of structure and mode of operation of my device without departing from its broad principle of providing, as a stencil means, a continuous strip of flexible stencil elements, and associating therewith means for feeding cards successively into printing position with 45 respect to individual stencil units and means for printing upon said cards through said stencil units. Of course I do not limit myself to stencils of the coated tissue paper type as any other type 50 of stencil unit might serve.

Having thus fully described my invention, what I claim is—

1. In a device of the character specified, the combination of an endless stencil strip made up of 55 a group of individual stencil units and provided with perforations for engagement by actuating means, a sprocket roller provided with teeth for engaging said strip through said perforations for actuating the same, a printing roller, a platen 60 roller arranged to cooperate with said printing roller, means for supplying ink to said printing roller, means for supporting said stencil strip and guiding the same above and around said printing roller and between said printing and said platen 65 rollers, said supporting and guiding means comprising a first curved plate located above said ink supplying means and said printing roller and a second curved plate located and arranged so as to direct said strip between said printing and platen 70 rollers, and means for feeding sheets to be printed upon by said individual stencil units successively into engagement with said strip, in a manner whereby each of said sheets may register with a single stencil unit, successive sheets registering 75

- with successive stencil units as said sheet and stencil unit pass between said rollers.
2. In a device of the character specified, the combination of an endless stencil strip made up of a group of individual stencil units and provided with perforations for engagement by actuating means, a sprocket roller provided with teeth for engaging said strip through said perforations for actuating the same, means for retaining said stencil strip in engagement with opposite parts of the periphery of said sprocket roller in a manner whereby loops are formed by said stencil strip to each side of said sprocket roller, a printing roller, a platen roller arranged to cooperate with said printing roller, means for supplying ink to said printing roller, means for supporting the loop formed by said stencil strip to one side of said sprocket roller and guiding the same above said printing roller and said means for supplying ink to the same and between said printing and platen rollers, and means for feeding sheets to be printed upon by said individual stencil units successively into engagement with said strip, in a manner whereby each of said sheets may register with a single stencil unit, successive sheets registering with successive stencil units as said sheets and stencil units pass between said rollers.
3. In a device of the character specified, the combination of an endless stencil strip made up

of a group of individual stencil units and provided with perforations for engagement by actuating means, a sprocket roller provided with teeth for engaging said strip through said perforations for actuating the same, means for retaining said stencil strip in engagement with opposite parts of the periphery of said sprocket roller in a manner whereby loops are formed by said stencil strip to each side of said sprocket roller, a printing roller, a platen roller arranged to cooperate with said printing roller, means for supplying ink to said printing roller, means for supporting the loop formed by said stencil strip to one side of said sprocket roller and guiding the same above said printing roller and said means for supplying ink to the same and between said printing and platen rollers, means for actuating said sprocket roller and said printing and platen rollers in a manner whereby their respective peripheral speeds may be substantially the same, and means for feeding sheets to be printed upon by said individual stencil units successively into engagement with said strip, in a manner whereby each of said sheets may register with a single stencil unit, successive sheets registering with successive stencil units as said sheets and stencil units pass between said rollers.

HARMON P. ELLIOTT.
